CLAIM

The ornamental design for an electric brush, as shown and described.

DESCRIPTION

FIG. 1 illustrates a perspective view of an electric brush; FIG. 2 illustrates a front view of the electric brush thereof; FIG. 3 illustrates a back view of the electric brush thereof; FIG. 4 illustrates a left side view of the electric brush thereof,

FIG. 5 illustrates a right side view of the electric brush thereof;

FIG. 6 illustrates a top view of the electric brush thereof, FIG. 7 illustrates a bottom view of the electric brush thereof; and,

FIG. 8 illustrates an exploded view of the electric brush thereof.

In the drawings, the broken lines illustrate portions of the article and form no part of the claimed design.
